UNITED STATES PATENT OFFICE

155,963

DESIGN FOR A CONTAINER FOR LIQUIDS

Edward V. Alvarez, Los Angeles, Calif., assignor
to The Plas-Tex Corporation, Los Angeles,
Calif., a corporation of Nevada

Application September 3, 1948, Serial No. 148,463

Term of patent 14 years

(Cl. D58—17)

To all whom it may concern:

I, Edward V. Alvarez, a citizen of the United States, residing at Los Angeles, county of Los Angeles, State of California, have invented a new, original, and ornamental Design for a Container for Liquids, of which the following is the specification, reference being had to the accompanying drawing, constituting a part thereof.

Fig. 1 is a perspective view of a container for liquids with the slide closure in open position, showing my new design;

Fig. 2 is a side elevation thereof with the slide closure in closed position;

Fig. 3 is a side elevation of Fig. 2 viewed from the right thereof; and

Fig. 4 is a plan view of Fig. 2.

I claim:

The ornamental design for a container for liquids, substantially as shown.

EDWARD V. ALVAREZ.
